UNITED STATES PATENT OFFICE.

VIRGIL L. MOORE, OF SAN RAFAEL, CALIFORNIA.

BICYCLE LUGGAGE-CARRIER.

SPECIFICATION forming part of Letters Patent No. 624,669, dated May 9, 1899.

Application filed January 17, 1899. Serial No. 702,441. (No model.)

To all whom it may concern:

Be it known that I, VIRGIL L. MOORE, a citizen of the United States, residing at San Rafael, county of Marin, State of California, 5 have invented an Improvement in Bicycle Luggage-Carriers; and I hereby declare the following to be a full, clear, and exact description of the same.

My invention relates to a luggage-carrier 10 which is especially designed for use upon bicycles.

It consists, essentially, of a flexible netting, a rectangular frame, to which the upper edge of the netting is secured, the lower portion 15 being closed, a bar having curved hooks, and loops adapted to engage the handle-bar and the vertical steering-post of the machine, so as to secure it thereto, said bar having loops formed in its ends, which are engaged by corresponding loops or links in the net-carrying 20 bar, whereby the latter is allowed to fold and automatically adjust itself with relation to the frame of the machine and to any load which may be placed in it.

25 The invention also consists in a means for securing the central link to the steering-post and in details of construction, which will be more fully explained by reference to the accompanying drawings, in which—

30 Figure 1 is a view showing the application of my device to the bicycle handle-bar and fully opened out. Fig. 2 shows the frame only with its attachments. The dotted lines show it folded and out of use.

35 A is a rectangular frame, preferably made by bending a sufficiently rigid wire to form a front and two ends, and at the rear these ends are bent to form loops *a*. B is a similar wire which forms the back of the frame and 40 the attachment to the handle-bar. This wire has its end bent to form loops *b*, which loosely connect with the loops *a*, so that the bar A can turn freely about its connection with the bar B. The loops *b* are formed by bending 45 the wire B approximately at right angles with the bend of the loops *a*, thence carrying the wire upward and forming curved hooks C, which are adapted to fit over the handle-bar of the machine, and these hooks are prefer- 50 ably covered with rubber or other flexible

coating to prevent marring of the bar or rattling. The center of the bar B is bent in reverse curves, as shown at D, being first carried backward to a depth somewhat greater than the diameter of the steering-post and 55 then bent horizontally forward, the bight E forming a curvature of such diameter as to fit around the steering-post, and thus prevent any end movement of the bar B after the ends have been put over the handle-bar F, as 60 shown. This central curve or bight E is also protected with rubber or other flexible material for the same reason as previously described.

G is a network, preferably woven of sufficient 65 stout cords made in the manner of a fish-net and connected with the front and ends of the bar A and also with the bar B, so as to form an open-work back which depends from these supporting-bars. 70

When the device is to be attached to the machine, it is only necessary to slip the bight E of the bar B over the approximately vertical standard-post and at the same time spring the bar B so that the hooks C at the 75 ends will hook over the handle-bar. The device is then held in place by the elasticity of the bar B, and when there is nothing in the net the bar A will swing downwardly by reason of the interlocking loops *a* *b* and will 80 lie closely against the front of the steering-post and entirely out of the way. Any article placed in the bag will cause the front of the bag A to swing forward sufficiently to accommodate it, and if the bag be filled the bar 85 A will stand approximately horizontal and retain the articles which are placed in the net.

In some cases it will be found desirable to secure the bar B to the post by a permanent fastening. I have therefore shown a hook H 90 pivoted to one side of the rear portion of the bight E, and the shank of the hook is long enough so that the hook may be made to engage the other side of the bight behind the steering-post, thus inclosing the latter and 95 securing the bar B firmly in place. This is especially useful in applying the carrier to that class of machines in which the handle-bars are very much dropped from the head toward the outer ends, and when thus secured 100

the outer ends of B may be bent downward, so as to be placed in any convenient or desired position.

I do not claim, broadly, a network or a rigid supporting-frame therefor; but,

Having described my invention, what I claim as new, and desire to secure by Letters Patent, is—

1. A luggage-carrier consisting of a frame forming the front and two ends, having eyes formed at the rear of the end sections, in combination with a bar forming the rear, said bar having eyes loosely engaging those of the front bar whereby the latter swings about said eyes and lies in a substantially vertical position resting against the front of the machine below the handle-bar when the carrier is empty, hooks bent at the ends to engage the handle-bar and a central bight engaging the steering-post and a flexible network having its upper periphery fixed to the said bars.

2. A luggage-carrier comprising a bar having a central bight formed by bending the bar backward and forward upon itself, hooks formed by bending the ends upon themselves so that hooks will clasp and engage the handle-bar and eyes formed in the bending of said hooks, a front bar approximately par-

allel with the previously-named bar having the ends bent at right angles and loops formed in said ends engaging the loops in the end of the first-named bar whereby the front bar swings freely in vertical planes upon the rear one and automatically adjusts itself to the amount of the luggage carried and a network of interlaced cords forming a back, the upper edges of which are secured around the front and rear bars.

3. A luggage-carrier consisting of front and rear net-carrying bars having their meeting ends swiveled together, hooks formed by bending the ends of the rear bar so as to engage the handle-bar, a central bight formed in said rear bar by folding the wire backward and forward upon itself and adapted to engage the steering-post of the machine, and a hook swiveled to one side of the said bight adapted to hook into the other side behind the steering-post.

In witness whereof I have hereunto set my hand.

VIRGIL L. MOORE.
